UNITED STATES PATENT OFFICE.

ROBERT H. SUETTINGER, OF TWO RIVERS, WISCONSIN.

SWINGING-SASH HOLDER.

1,234,957.

Specification of Letters Patent.

Patented July 31, 1917.

Application filed May 3, 1917. Serial No. 166,074.

To all whom it may concern:

Be it known that I, ROBERT H. SUETTINGER, a citizen of the United States, and resident of Two Rivers, in the county of 5 Manitowoc and State of Wisconsin, have invented certain new and useful Improvements in Swinging-Sash Holders; and I do hereby declare that the following is a full, clear, and exact description thereof.

10 My invention relates to new and useful improvements in means for holding storm or screen sashes, or other pivotally mounted members at a desired variable inclination as to the window frame or other support.

15 A common inconvenience encountered in adjustable holding means of this nature heretofore provided is that when the swinging sash is held at only a slight angle to the window frame, the holding arms of the sash 20 project inwardly of the path of movement of the sliding sashes of the window, to prevent closing the sliding sash without first manipulating the holding means. It is therefore primarily the object of my invention to provide a means whereby the swinging sash may be held in various desired positions without affecting the freedom of movement of the sliding sash of the frame.

25 A further object resides in the provision 30 of a sash holding device having its parts arranged for interchangeable association whereby the device may be disposed at either the right or left hand side of the window frame.

35 With the above and other objects and advantages in view, the invention resides more particularly in the novel combination, arrangement and formation of parts hereinafter described and pointed out in the ap- 40 pended claims.

In the drawings

Figure 1 is an elevational view of my improved sash holding device associated with a window frame and a swinging sash 45 member.

Fig. 2 is a detail view showing my device arranged for holding the swinging sash in an intermediate position.

Fig. 3 is a perspective view of the keeper 50 member and adjacent portion of the holding arm of my device.

Referring now more particularly to the accompanying drawings, 5 designates a window frame, having the usual sash retaining 55 strip 6 secured to one side thereof, and 7 designates a swinging sash associated with the

window. 8 designates one of the usual sliding sashes of the window.

My improved sash holding device includes a keeper plate 9 secured to the retaining strip 6 and having one side portion bent outwardly and provided with an open slot 10 reduced adjacent its outer free end. Pivoted to an ear 11 on the swinging sash 7 is one section 12 of the holding arm of my device, and pivotally connected with this section 12 is a second section 13 which has its free end directed laterally to form a finger piece 14, and which is provided in its top and bottom edges immediately inwardly of 60 the finger piece with recesses 15, each adapted to receive an edge portion of the slot 10 of the keeper plate. It is noted that the width of the holding arm sections is greater than the width of the reduced portion of the 65 slot 10, whereby the holding arm is normally retained against lateral displacement from the keeper slot, and to facilitate engagement and disengagement of the arm and keeper plate when desired, the intermediate portion of the arm section 13 is cut away at 16. The pivotal connection of the 70 arm sections comprises a bolt 17 passed through the adjacent ends of the sections, and the end of the section 12 is reduced to 75 form consequent upper and lower shoulders 18, while the end of the section 13 is provided with an outwardly offset projection 19 adapted to abut the uppermost shoulder 18 to limit downward pivotal movement of the 80 arm section 12. The lower shoulder 18 is adapted to abuttingly engage the lower edge of the slot 15 to hold the swinging sash 7 in an intermediate position, it being 85 noted that the reduction of the end of the arm section 12 forms a recess in conjunction 90 with the adjacent edge of the section 13.

By thus hinging the holding arm adjacent its intermediate keeper engaging portion, the free end of the arm may swing downwardly when not in use, as shown in Fig. 2, to permit free movement of the sliding sash 8, and it will be appreciated that any number of hinged sections and intermediate keeper engaging portions may be provided 100 105 as desired.

By the provision of recesses 15 in both edges of the arm section 13, and by the provision of a pair of shoulders 18, both the right and left hand holding arms may be 110 stamped by a single die, and the finger piece 14 and the end of the stop projection 19 may

be subsequently bent in either desired direction.

What is claimed is:

1. A device of the character described comprising a section adapted for pivotal securement to a swinging sash member and having one end reduced to define consequent shoulders, a second section pivoted to said end of the first section, a projection on the second section engaging one of the shoulders to provide a limit of movement, and a keeper member for receiving the sections, the other shoulder of the first section forming a recess with the second section when partly folded and engaging said keeper member substantially as described.
2. A device of the character described comprising a section adapted for pivotal securement to a swinging sash member and having one end reduced to define consequent shoulders, a second section pivoted to said

end of the first section and provided with recesses in its free end, a keeper member provided with a slot for receiving the sections, said keeper engaging said recesses 25 when the sash member is in full extended position, and a projection on the second section engaging one of the shoulders to provide a limit of movement, said other shoulder forming a recess in conjunction with the second section and adapted for engagement with said keeper whereby the swinging sash may be held in partly open position without affecting the freedom of movement of the sliding sash of the frame to which 30 the device is attached substantially as described.

In testimony that I claim the foregoing I have hereunto set my hand at Milwaukee, in the county of Milwaukee and State of 40 Wisconsin.

ROBERT H. SUETTINGER.
